CLAIM

What is claimed is an ornamental design for a rear grille surround for a dumper, as shown and described.

DESCRIPTION

FIG. 1 is a front, top, right perspective view of a rear grille surround for a dumper;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a rear, top, right perspective view thereof; and,

FIG. 9 is a front, top, left perspective view thereof, shown installed on a dumper, wherein the broken lines forming the dumper show environmental subject matter for illustrative purposes only and form no part of the claimed design.
